US00D878441S

(12) **United States Design Patent** (10) Patent No.: **US D878,441 S**
(45) Date of Patent: **** Mar. 17, 2020**

(54) **SELF-PROPELLED ROBOT AND/OR
REPLICA THEREOF**

(71) Applicant: **HONDA MOTOR CO., LTD.**, Tokyo
(JP)

(72) Inventor: **Satoshi Hayashi**, Wako (JP)

(73) Assignee: **HONDA MOTOR CO., LTD.**, Tokyo
(JP)

(**) Term: **15 Years**

(21) Appl. No.: **29/649,796**

(22) Filed: **Jun. 1, 2018**

(30) **Foreign Application Priority Data**

Dec. 6, 2017 (JP) 2017-027277

(57) **CLAIM**

The ornamental design for a self-propelled robot and/or replica thereof, as shown and described.

DESCRIPTION

FIG. 1 is a front view of a self-propelled robot and/or replica thereof;

FIG. 2 is a rear view thereof;

FIG. 3 is a plan view thereof;

FIG. 4 is a left side view thereof;

FIG. 5 is a front perspective view as seen from the right side thereof;

FIG. 6 is a rear perspective view as seen from the right side thereof; and,

FIG. 7 is a reference front view projecting a face image onto an upper portion thereof.

The broken lines in the drawings illustrate portions of the self-propelled robot and/or replica thereof that form no part of the claimed design.

1 Claim, 4 Drawing Sheets
